ATTORNEYS.

UNITED STATES PATENT OFFICE.

HENRY MARLOW, OF NEW ROCHELLE, NEW YORK.

DESIGN FOR A TOY SAVINGS-BANK.

No. 39,902.

Specification for Design.

Patented March 30, 1909.

Application filed November 11, 1908. Serial No. 462,174. Term of patent 7 years.

To all whom it may concern:

Be it known that I, HENRY MARLOW, a citizen of the United States, residing at New Rochelle, in the county of Westchester and State of New York, have invented a certain new, original, and ornamental Design for Toy Savings-Banks, reference being had to the accompanying drawing, which shows my design.

The figure is a perspective view showing the design of the bank.

I claim;

The ornamental design for a toy savings bank as shown.

HENRY MARLOW.
